UNITED STATES PATENT OFFICE.

LOUIS P. CHICOINE, OF VAUDREUIL, QUEBEC, CANADA.

TRACK LINER.

Application filed March 3, 1923. Serial No. 622,710.

To all whom it may concern:

Be it known that I, LOUIS P. CHICOINE, of the town of Vaudreuil, Province of Quebec, Dominion of Canada, a subject of the King of Great Britain, have invented certain new and useful Improvements in Track Liners; and I do hereby declare that the following is a full, clear, and exact description thereof.

10 My invention relates to track aligning tools of the type illustrated in my United States Patent No. 1,387,688, granted August 16, 1921, and has for its object to provide a tool of this type which will be more efficient, more durable and which can be manufactured at a comparatively low cost.

To this end my invention consists of the combination, construction and particular arrangement of the parts hereinafter described 20 and illustrated and pointed out in the claims.

For full comprehension, however, of my invention, reference must be had to the accompanying drawings in which similar reference characters indicate the same parts, and wherein:

Figure 1 is a side elevation of my improved track liner;

Figure 2 is a plan view thereof;

Figure 3 is a longitudinal sectional view taken on line 3—3 Figure 2;

Figure 4 is a transverse sectional view taken on line 4—4 Figure 2; and

Figure 5 is a fragmentary sectional view 25 of the lever holding means.

Referring to the accompanying drawings a fulcrum member adapted to form an extended bar or base for the aligning lever is indicated at 2. This fulcrum member is 40 comparatively shallow and is adapted to be inserted between the ballast and the bottom of the rail to be aligned, this shallowness enabling it to be inserted without necessitating the clearing away of the ballast 45 which usually must be done with tools of this type before the tool can be positioned for use. This fulcrum member preferably consists of a unitary casting substantially oblong in plan view and of a width which 50 will enable it to be readily positioned between the ties and having a flat unobstructed top 3 which facilitates the positioning. One end is tapered to form a blunt nose or point 4, the tapered portion towards its point 55 being inclined downwardly as at 5 and of increased thickness.

To provide means for firmly anchoring the fulcrum upon the road bed it is provided with downwardly extending longitudinal side flanges 6 and 7 and a corresponding transversely disposed flange 8 located at the rear end of the member, or in other words at that end farthest from the rail when in use. The opposite ends of this transverse flange merge with the side flanges. This transverse flange is of greater depth than the side flanges and its ends are sheared off as at 9 to enable it to be easily anchored in the ballast. The side flanges extend from the transverse flange to the nose 60 of the fulcrum and are tapered as at 10 as they approach the same, and each is provided with a downwardly extended middle portion 12 having inclined sides 13 terminating in a blunt point in a shape similar 65 to that of the rear flange to further assist in the anchoring of the fulcrum member. These downwardly extending portions also provide bearings for a hinge pin 14, the outer ends of which are journalled in openings 15 in the flanges. This hinge pin is disposed transversely to the length of the fulcrum and is located in rear of the centre line of the mass of the latter a distance sufficient to impart to the nose a tendency to 70 swing down when the liner is lifted and as this downward movement is limited by the rear end of the fulcrum engaging the lever holding means about to be described, the fulcrum is maintained in a horizontal position. The pin 14 hinged carries the means 75 for holding the lever upon the fulcrum member. This means is designed to permit the use of the ordinary crowbar or liner bar which forms a necessary part of the track- 80 man's equipment so that the expense of a special bar is avoided and the bulk and weight of the tool considerably reduced. This is of considerable importance in railway work as it is imperative that the equipment 85 to be carried occupies minimum space, and is as inexpensive and as light in weight as will reasonably permit. The holding means consists of a plate-like arm 16 hinged at its lower end upon the pin 14 and positioned within an opening or depression 17 in the fulcrum member, the longitudinal side edges of the member at the opening being turned downwardly in the form of flanges 18 and 19 which conform to the 90 shape of the flanges 6 and 7 and which for reinforcement purposes are extended for 95 increased strength.

wardly as at 20 to the thickened nose of the member.

The bottom edges of the rear ends of the flanges 18 and 19 are united by a seat 21

5 which is preferably inclined to provide a flat bearing for the arm when the latter is lying prone thereon. The hinge pin 14 and the seat 21 are located a sufficient distance below the top of the fulcrum member to position the 10 holding means entirely below the top when such means is lying prone upon its seat thereby providing an unobstructed top which is only broken by the crowbar or liner bar 25 which is inclined upwardly therefrom. This

15 enables the tool to be inserted beneath the rail to a point at which the bar itself contacts with the adjacent base flanges as indicated in Figure 1, and consequently making easier the aligning operation.

20 In order to provide means for detachably securing bars of different sizes upon the holding arm, its hinged end has a retaining member preferably constructed in the form of a metal strap of inverted U-form formed

25 integrally with the arm, the top wall of the strap being inclined as at 26 to provide a tapered opening through which the end of the bar is inserted, the reduced end of the opening limiting longitudinal displacement of

30 the bar in a downward direction. The extent of the projection of the bar beyond the end of the strap may be varied by inserting a wedge or wedges 27 as indicated in Figure 5, it being desirable for instance on sand ballast to have the bar extending a greater 35 distance beyond the strap than would be required on a harder road bed for the purpose of providing additional means for preventing displacement of the fulcrum member.

40 The holding arm extends rearwardly from its hinged end to any desired extent and its rear end is enlarged as at 28 and provided with holes 29 which receive the threaded legs

45 30 of a staple 31, the latter straddling the bar and clamping it upon the arm, the clamping action being obtained by butterfly nuts 32 which are screwed upon the legs. To exert minimum strain upon the holding

50 arm at the fulcrum point the hinge pin is so positioned therein that its top coincides or extends slightly above the top surface of the arm so that the pressure of the bar is exerted directly upon the pin as indicated in Figure 5.

55 What I claim is as follows:—

1. In a track liner a fulcrum member, means hinged upon the fulcrum member and adapted to receive a rail-engaging lever, the hinged point being fixed and located in rear

60 of the transverse centre line of the mass of the fulcrum member.

2. In a track liner a fulcrum member, means hinged upon the fulcrum member and adapted to receive a rail-engaging lever, the hinged point being fixed and located in rear

of the transverse centre line of the mass of the fulcrum member, and means for detachably clamping the lever upon the hinged means.

3. In a track liner a fulcrum member, 70 means hinged upon the fulcrum member and adapted to receive a rail-engaging lever, the hinged point being fixed and located in rear of the transverse centre line of the mass of the fulcrum member; means preventing longitudinal displacement of the lever, and means for detachably clamping the lever upon the hinged means.

4. A fulcrum member adapted to be hingedly and detachably connected to the lower 80 end of a standard liner bar and form a fulcrum thereon upon the ballast of the road-bed, the fulcrum member being constructed and arranged to permit the insertion of the bar under the rail during the aligning operation and the hinge point being located in rear of the transverse centre line of the mass of the fulcrum member.

5. A fulcrum member adapted to rest 90 upon the ballast of the road-bed, means hinged upon the member and adapted to receive a standard liner bar, said fulcrum member and hinged means being constructed and arranged to permit the insertion of the liner beneath the rail to be aligned a distance sufficient to locate the bar beneath the rail, and said hinged means being so connected to the bar that the latter is permitted to directly contact with the rail when aligning the same.

6. A track liner consisting of unitary fulcrum member and means for detachably and hingedly securing a standard liner bar thereon, said hinge point being fixed and located between the centre line of the mass of 105 the member and its end farthest from the rail to be aligned, said fulcrum member having a depression in its top adapted to accommodate the adjacent portion of the liner bar when the latter is lying prone upon the member whereby the liner may be inserted to position with the bar located beneath a rail to align the same.

7. In a track liner a fulcrum member 115 adapted to rest upon the ballast of the road bed when aligning a rail consisting of a unitary member adapted to provide an extended bearing, said member having a flat unobstructed top with a longitudinal depression therein, means hinged upon the member and disposed longitudinally within the depression, a lever secured upon said hinged means, said last mentioned means being located substantially below the said top when lying prone upon the fulcrum member whereby 125 the liner may be inserted to position with the bar located beneath the rail to be aligned.

8. In a track liner a fulcrum for a lever consisting of a unitary member adapted to provide an extended bearing for the lever, 130

- said member having a flat unobstructed top with a longitudinal depression therein, means hinged upon the member and disposed longitudinally within the depression, 5 said last mentioned means being located entirely below the said top when lying prone upon the fulcrum member, and means for detachably clamping the lever upon the hinged means.
10. 9. In a track liner a unitary fulcrum member of plate form presenting a flat top free from obstruction and having a longitudinal opening extending from a point inward from its rear end to within close proximity of the latter, that portion of the member between the opening and such rear end being depressed throughout its length and forming an inclined seat located below the top of the member, said rear end having 15 a transverse downwardly extending flange terminating in downwardly extending flanges at the longitudinal sides of the member, the front end of the member being tapered.
20. 10. In a track liner, a fulcrum member consisting of a member of plate form presenting a flat top free from obstruction and having a longitudinal opening extending from a point inward from its rear end to within close proximity of the latter, that portion of the member between the opening and such rear end being depressed throughout its length and forming an inclined seat located below the top of the member, said rear end having a transverse downwardly extending flange terminating in downwardly extending flanges at the longitudinal sides of the member, the front end of the member being tapered, and lever holding means 25 hinged upon said member and adapted to lie within the depression and below the top of the member when prone upon the latter.
11. In a track liner, a fulcrum member of plate form presenting a flat top free from obstruction and having a longitudinal opening extending from a point inward from its rear end to within close proximity of the latter, that portion of the member between the opening and such rear end being depressed throughout its length and forming an inclined seat located below the top of the member, said rear end having a transverse downwardly extending flange terminating in downwardly extending flanges at the longitudinal sides of the member, the front end of the member being tapered to a blunt point in plan view, and lever holding means hinged upon said member and adapted to lie within the depression and below the top of the member when prone upon the latter, and means for detachably securing a lever upon said last-mentioned means.
12. In a track liner, a fulcrum, means hinged upon the fulcrum and adapted to support a lever in position with the latter 65 bearing directly upon the hinge pin.
13. In a track liner, a fulcrum, means hinged upon the fulcrum and adapted to receive a lever, said means consisting of an arm having a top surface upon which the lever rests, and a pin hingedly supporting the arm, the uppermost point of the periphery of the pin substantially coinciding with the said surface for the purpose of enabling the lever to bear directly thereon. 75
14. In a track liner, a fulcrum member, means hinged upon the member and adapted to support a lever, said means consisting of an arm having a retaining strap at its lower end forming a socket open at both 80 ends and adapted to receive the lever, and means for clamping the lever in position upon the arm.
15. In a track liner, a fulcrum member, means hinged upon the member and adapted to support a lever, said means consisting of an arm having a retaining strap at its lower end forming a socket open at both 85 ends and adapted to receive the lever, means for clamping the lever in position upon the arm, said socket being tapered towards its lower end.
16. In a track liner, a fulcrum member, means hinged upon the member and adapted to support a lever, said means consisting of an arm having a retaining strap at its lower end forming a socket open at both 90 ends and adapted to receive the lever, means for clamping the lever in position upon the arm, said socket being tapered towards its lower end and means for adjusting the extent to which the lever projects beyond the lower end of the socket. 95
17. In a track liner, a fulcrum member, means hinged upon the member and adapted to support a lever, said means consisting of an arm having a retaining strap at its lower end forming a socket open at both 100 ends and adapted to receive the lever, means for clamping the lever in position upon the arm, said socket being tapered towards its lower end and means for adjusting the extent to which the lever projects beyond the lower end of the socket. 105
18. A track liner consisting of a shallow plate-like fulcrum member having a flat unobstructed top with a longitudinal opening therein extending from a point inward from its rear end to within close proximity of the latter and that portion between the opening and the rear end being depressed to 110 form a seat, means for resisting displacement of the member when in use consisting of downwardly extending flanges located at the longitudinal sides of the member and of the opening and at the rear transverse side of the member, the front of the latter being tapered, an arm hinged upon the member within the opening and adapted to 115
- 120
- 125

- be located entirely below the top of the member when lying prone, said arm having a tapered socket at its lower end, such socket being open at both ends and adapted to receive a lever and a clamp bolted to the upper end of the arm for securing the lever thereon.

In testimony whereof I have signed my name to this specification in the presence of two witnesses.

LOUIS P. CHICOINE.
